UNITED STATES PATENT OFFICE.

DAVID E. TILLMAN, OF SELMA, ALABAMA.

RESILIENT NON-COLLAPSIBLE TIRE.

1,186,453.

Specification of Letters Patent. Patented June 6, 1916.

Application filed October 5, 1915. Serial No. 54,228.

To all whom it may concern:

Be it known that I, DAVID E. TILLMAN, a citizen of the United States, residing at Selma, in the county of Dallas and State of Alabama, have invented new and useful Improvements in Resilient Non-Collapsible Tires, of which the following is a specification.

This invention relates to resilient tires, and the object in view is to provide what I term a resilient non-collapsible core or supporting member for the outer casings of the present day pneumatic tires, the said core forming an efficient support for the outer casing and doing away entirely with the inflation of the tire by means of air and thereby rendering the tire as a whole immune from punctures and blow outs and the annoyance, delay and other troubles incident to the use of pneumatic tires.

With the above general object in view, the invention consists in the novel construction, combination and arrangement of parts, as herein described, illustrated and claimed.

In the accompanying drawings:—Figure 1 is a cross section through a complete tire showing the resilient core of this invention in its applied relation to an outer casing of the clincher type. Fig. 2 is a fragmentary perspective view of the resilient annulus broken away to show the relation of the springs thereto.

An ordinary outer casing is shown at 1, the same being illustrated as of the clincher type, being provided with the usual clincher beads 2 along the longitudinal margins thereof.

In carrying out the present invention, I provide a resilient annulus designated generally at A, said annulus being formed of rubber and embodying a transversely arcuate body 3 which is split or divided longitudinally at 4 and provided with outwardly extending marginal portions 5 of hook shape in cross section so as to embrace the clincher beads 2 of the outer casing 1 as clearly illustrated in the drawings. Centrally of the tread portion of the resilient annulus A there is an inwardly extending resilient rib 6 which runs longitudinally around the inner face of the annulus. This rib is preferably solid in cross section and is also formed in cross section in such a shape that the maximum width thereof is at a point remote from the tread portion of the annulus. In other words, the rib 6 is

reduced in width adjacent to its junction with the body of the annulus 3 the purpose of which will be presently explained.

In conjunction with the resilient annulus 60 shaped as hereinabove described, I employ an annular series of springs all of corresponding shape and preferably arranged in slightly spaced relation to each other, each of said springs being bent to form a substantially arched or arcuate main body portion 7 and an inwardly depressed central portion 8 which is in the form of an open sided loop corresponding in shape to the shape of the rib 6 so as to embrace said rib 70 and thereby cause the annulus and spring to be held together. In this way all of the springs are fastened to the inside of the resilient annulus and the latter acts to hold all of the springs in proper spaced relation 75 to each other. Each spring tapers or is gradually reduced in width from the outer central portion thereof toward the ends thereof and the ends of each spring are bent outwardly to form hook shaped portions 9 which embrace the corresponding portions 5 of the resilient annulus A.

As shown in Fig. 1, the outwardly turned marginal portions of the resilient annulus and likewise the outwardly turned hook shaped end portions of all of the springs embrace the clincher beads of the outer casing 1 of the tire and in this way the complete resilient core is held in the proper relation to the outer casing. In case one of the springs should become fractured, the parts thereof may be removed and a new spring readily substituted therefor without disturbing the remainder of the tire. A tire equipped with the resilient core of this invention is proof against punctures, blow outs and the like, is self-supporting and requires no inflation. The same resiliency and elasticity is provided as in an inflated pneumatic tire and the action of the springs 90 within the annulus is rendered particularly effective by reason of the fact that a central pull inwardly is obtained on each spring by reason of the relationship existing between the looped central portion of each spring 100 and the inwardly extending annular rib 6. Furthermore, as the rib 6 is pressed inwardly the effect is to cause the portions of each spring at opposite sides of the rib to more firmly clamp or bind against said rib 105 thereby avoiding any tendency of the springs to shift or creep longitudinally of

the annulus. Furthermore, it will be understood that the annulus by reason of the rib 6 straddles all of the springs and serves as a stringer for the entire annular series of 5 springs.

Having thus described my invention, I claim:

1. A resilient core insertible in and removable from an unmounted outer casing, said 10 core embodying a resilient annulus in the form of a rubber tube split longitudinally along its rim face and having its longitudinal margins extended outwardly, an annular series of springs each having a generally 15 arched main portion extending transversely of said annulus and also having outwardly extending end portions embracing the outwardly extended longitudinal margins of said annulus, and an internal resilient annular spring retaining rib extending longitudinally of the annulus, said rib engaging and holding the springs against displacement and in a definite relation to the annulus when the core and outer casing are separated.
- 25

2. In a tire, a resilient core insertible in and removable from an outer casing, said core embodying a resilient annulus in the form of a rubber tube split longitudinally along its rim face, an annular internal resilient rib extending longitudinally of the tread portion of said annulus and formed in such shape in cross section that the maximum width thereof is remote from the junction of the rib with the tread portion of the annulus, and an annular series of springs each having a generally arched main portion extending transversely of said annulus and also having outwardly extending hook shaped end portions embracing the 40 longitudinal margins of said annulus, each spring being further shaped centrally to form an open loop which embraces said rib and holds the spring and annulus together.

In testimony whereof I affix my signature 45 in presence of two witnesses.

DAVID E. TILLMAN.
